Office Action for Japanese Design Application No. 2023-007376, issued Feb. 13, 2024 (with English translation).

Primary Examiner — Patricia A Palasik(74) *Attorney, Agent, or Firm* — Knobbe Martens Olson & Bear LLP(57) **CLAIM**

The ornamental design for a mobile robot, as shown and described.

DESCRIPTION

FIG. 1 is a top, front, and left side perspective view of an embodiment of the design for a mobile robot.

FIG. 2 is a top, rear, and right side perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof; and,

FIG. 8 is a bottom plan view thereof.

Broken lines are used to illustrate features of the mobile robot that form no part of the claimed design.

1 Claim, 6 Drawing Sheets(56)
